(57) **CLAIM**

The ornamental design for an end piece for a seat, as shown and described.

DESCRIPTION

FIG. 1 is a left side perspective view of an end piece for a seat, in accordance with a first embodiment of the present design;

FIG. 2 is a left side view of the end piece for a seat shown in FIG. 1;

FIG. 3 is a right side view of the end piece for a seat shown in FIG. 1;

FIG. 4 is a top view of the end piece for a seat shown in FIG. 1; and,

FIG. 5 is a perspective view of the end piece for a seat shown in FIG. 1 being depicted as a component of a table set. The broken lines shown in FIG. 5 depict other components of the table set and are included for environmental purposes only.
